SMOKING PIPE

Warren Fuhrmann, Kearney, N. J., and Thomas F. Powers, New York, N. Y.

Application August 10, 1938, Serial No. 224,004

11 Claims. (Cl. 131—176)

This invention relates to smoking pipes having a bowl arranged with a tobacco chamber having a mouth at one end of the bowl and a stem at the opposite end of the bowl having a bore communicating with the chamber, and it is the primary object of the invention to provide closure means for the chamber mouth adjustably mounted on the bowl to be positioned juxtaposed to the exterior wall of the bowl to permit filling of the chamber with tobacco, and after the tobacco has been lighted adapted to be positioned over the mouth to close the same and prevent the lighted tobacco leaving the chamber while smoking or after smoking.

It is another object of the invention to provide closure means for a smoking pipe whereby the closure means may be positioned from the chamber mouth to act as a wind shield while lighting the tobacco in the chamber.

It is a further object of the invention to provide the closure means with a portion which will remain cool while the closure means is in closed position and the pipe is being smoked, so that the fingers of the smoker will not be burned if said portion of the closure means is touched by the fingers.

It is a still further object of the invention to arrange closure means for the mouth of a pipe chamber with manipulating means remote from the closure means whereby the closure means may be actuated from the mouth during the smoking of the pipe without burning or injuring the fingers of the smoker.

Further objects and advantages of the invention will hereinafter appear in the detailed description of the invention.

In the drawing accompanying and forming a part of this application, Figure 1 is a side elevational view of the pipe showing in dot and dash lines the closure means adjusted to position to act as a wind shield in lighting the tobacco.

Figure 2 is an end view of the pipe looking at the left of Figure 1 and showing the closure means in full lines actuated to full open position juxtaposed to the exterior wall of the pipe bowl and in dot and dash lines in position intermediate the closed and open positions thereof.

Figure 3 is a fragmentary view of the pipe looking at the top of Figure 2 and showing the manner of slidably mounting the closure means.

Figure 4 is a plan view of a modified form of closure means prior to the final forming of the same.

Figure 5 is a side elevational view of the modi-

fied form of closure means shown in Figure 4 showing the same in finished form.

Figure 6 is a fragmentary view of the mouth portion of a pipe showing another modified form of closure means mounted thereon looking at the free end of the closure means.

Figure 7 is a view similar to Figure 6 with the closure means positioned perpendicularly of the mouth portion to show the under surface of the closure means.

In carrying out the embodiment of the invention illustrated in the drawing, there is provided a smoking pipe having a bowl 8 of rectangular or square shape in cross section provided with a tobacco chamber 9 extending longitudinally of the bowl with a mouth opening to one end of the bowl and terminating adjacent the opposite end constituting the bottom of the pipe and arranged with a stem 10 integral with the bowl and extending laterally and centrally from a side of the bowl having a bore 11 therethrough communicating with the bowl chamber 9. Chamber 9 is shown as being of circular shape in cross section, but may be of a shape corresponding to the cross section of the bowl. The stem 10 is of square contour to harmonize with the contour of the bowl and co-operate with the bottom of the bowl to support the pipe in upright position on a flat surface. The stem 10 is arranged at the free end for the removable engagement of a mouth piece 12.

To permit of the placing of the pipe in a pocket of the apparel of the user with part of the tobacco which has not been consumed in the pipe bowl, or with the tobacco lighted, and prevent the soiling or burning of the pocket by the tobacco, or tobacco ash spilling from the bowl chamber, or when placed elsewhere, as in a drawer with the possibility of starting a fire, adjustable closure means is provided for the mouth of the bowl chamber, comprising a flat plate 13 of substantially the same size and shape as the top of the bowl having a circular center portion 14 partially stamped therefrom with connecting sections 15 around the periphery bent from the plate to support the portion 14 in spaced relation to the body of the plate 13 and provide horizontal air passages between the center portion 14 and the plate 13, as at 16 in Figure 1. There are shown in the present instance four connecting sections 15 equidistantly spaced around the periphery of the center portion 14, but the number of said sections may vary depending on the area of air space desirable between the center portion and plate, and the

strength of the material used for the cover plate. To further induce a draft through the tobacco in the chamber 9, the center portion 14 is arranged with air passages, shown as a plurality of perforations or holes 17, but which may be a plurality of slots.

The closure plate 13 is adjustably mounted on the pipe bowl to be positioned over the mouth of bowl chamber and juxtaposed to a side wall 10 of the bowl with the chamber mouth open to permit filling the chamber with tobacco and lighting the same. This is accomplished by a 15 slidably member comprising a rectangular plate 18 of a length slightly greater than the width of the side walls of the bowl having the opposite ends flanged laterally, as at 19, and adapted to slidably engage elongated recesses 20 in the opposite side edges of a side of the pipe bowl. In the present instance, the recesses 20 are arranged in the side wall of the bowl opposite the wall integral with the stem 10, but the recesses may be arranged in and the slide plate 18 mounted on either of the side walls of the bowl adjacent the wall having the stem 10. The 25 flanged ends 19 and recesses 20 are arranged to prevent disengagement of said flanged ends from the recesses, as shown in Figure 3, by extending the recesses obliquely into the bowl and correspondingly bending the flanged ends. The 30 flanged ends may be bent to right angular form with the free angular sections engaging slots in the recesses which are of right angle shape in cross section. One side of the slide plate 18 is arranged with hinge knuckles 21 spaced from the flanged ends 19 to extend into a recess 22 in an end of the closure plate 13 juxtaposed to hinge knuckles 23 arranged on said end of the closure plate at opposite ends of the recess 22, whereby the closure plate is pivoted to the slide 35 plate by a pintle 24 engaged in the knuckles 21 and 23. The closure plate is yieldingly urged toward the mouth of the pipe chamber and the bowl wall arranged with the recesses 20 by a spring 25 coiled around the pintle between the 40 knuckles 21 with one end of the spring engaging the closure plate, as at 26, and the other end engaging the slide plate, as at 27. When the slide plate 18 is positioned adjacent the top of the pipe bowl, the closure plate will be urged by 45 the spring 25 to engage the top of the pipe bowl and cover the mouth of the bowl chamber by the center portion 14. The closure plate is removed from the top of the pipe bowl to uncover the chamber mouth by actuating the slide plate 18 toward the bottom of the pipe bowl, said actuation of the slide plate moving the closure plate over the edge of the bowl between the top and side wall arranged with the recesses 20 which will raise the free end of the 50 closure plate and position said plate at an angle to the top of the pipe bowl, as shown in dot and dash lines in Figure 1, and the continued movement of the slide plate 18 will position the closure plate juxtaposed to the bowl wall arranged with the recesses 20.

To facilitate the actuation of the slide plate 18, said plate is arranged with manipulating means by arranging the end of the plate opposite the knuckle end with an extension and curling said extension into a finger gripping member, as at 28. The actuating movement of the slide plate 18 is limited and said plate is prevented from being removed from the ends of the recesses 20 by abutments in the form of pins 29 65 fixed in the opposite ends of a recess 20, which

is of greater width than the other recess, and said pins being adapted to engage a projection 30 extending from the flange 19 engaged in the recess 20 of greater width. The pins 29 are positioned in the recess of greater width out of the path of travel of the flange 19 and the projection 30 is of a length to engage the slide of said recess and prevent canting of the slide plate.

The closure plate 13 may be readily adjusted to position juxtaposed to the side wall of the pipe bowl by the slide plate 18 to permit tamping of the lighted tobacco in the bowl chamber without injuring or burning the fingers of the user, as the finger grip 28 will remain cool due to the remote position thereof from the closure 15 plate.

The raising or spacing of the center portion 14 from the body of the closure plate will provide said plate with an air cooled portion which will prevent injuring or burning the fingers of the user if said center portion is accidentally touched by the user. In Figures 4 to 7, there are illustrated modified forms of the closure plate to carry out this purpose of providing the closure plate with an air cooled portion. 25

In Figures 4 and 5, the closure plate is substantially twice the length of the plate 13 shown in Figures 1 to 3, inclusive, to provide an additional end portion 31 having air passages therein such as perforations 32 or a radial series of 30 slots. The portion 31 is folded over the upper surface of portion 13 with an intermediate portion 33 spacing the portion 31 from the portion 13 a distance to permit sufficient circulation of air between said portions 13 and 31 to maintain the plate portion 31 cool and prevent injury to the fingers of the user. The air passages 32 will also reduce the amount of heat transmitting surface of the plate portion 31, which will aid in maintaining said portion cool. The plate 40 portion 31 may be arched to provide a pleasing appearance and extended to about the knuckles 23 of the plate portion 13. The structure of the slide plate of the modified closure plate 13, 31, 33 of Figures 4 and 5 is the same as shown in 45 Figures 1 to 3, inclusive, as indicated by the reference numerals.

In Figures 6 and 7, the entire closure plate 13, 14, 15, is spaced from the top of the pipe bowl to provide a passage for air between said plate and the chamber mouth by forming the closure plate from a blank of greater width whereby angular side portions are formed having a vertical section 34 and a horizontal section 35 extending parallelly of the plate 13 to engage the top of 55 the pipe bowl. Said blank will also have lateral extensions extending from the sides thereof adjacent the knuckles 23 to form horizontal portions 36 to engage the top of the pipe bowl adjacent the side arranged with the recesses 20. 60 The free end of the closure plate 13 is extended slightly beyond the angular side portions 34, 35 and bent inwardly to form a lip 37 partly closing the space between the closure plate and the top of the pipe bowl, as shown in Figure 6, to prevent 65 the escape of ashes from the tobacco chamber but permitting air to pass between said lip and the pipe bowl.

The center portion 14 of the closure plate 13 in the Figures 6 and 7 structure is shown of ar- 70 cuate shape in cross section and the center portion 14 of the Figures 1 to 3, inclusive, and Figures 4 and 5 structures may be of the same formation instead of being flat as shown in said figures. The space between the portion 14 and 75

the body of the closure plate 13 is large enough to permit passage of sufficient air to cool said center portion but too small to permit the escape of ashes from the tobacco chamber.

5 To facilitate the lighting of the tobacco in the pipe chamber outdoors, the slide plate 18 is adjusted to position the closure plate 13 to extend at an angle to the chamber mouth, as shown in dot and dash lines in Figure 1. The angular position of the closure plate is varied by the adjustment of the slide plate toward and away from the chamber mouth.

Having described our invention, we claim:

15 1. In a smoking pipe, a bowl arranged with a chamber having a mouth at one end and an integral stem having a bore communicating with the chamber, and a closure plate for the mouth of the chamber pivotally and slidably mounted to extend over the chamber mouth in one extreme position thereof and to extend juxtaposed to the exterior wall of the bowl in the other extreme position with the mouth exposed and whereby the sliding movement of the closure plate causes pivotal movement thereof.

25 2. In a smoking pipe, a bowl of rectangular shape in cross section arranged with a chamber extending longitudinally of the bowl and having a mouth at one end of the bowl and an integral stem extending laterally from a side of the bowl at the opposite end thereof and having a bore communicating with the chamber, a member slidably mounted on another side of the bowl, and a closure plate for the chamber mouth pivotally mounted on the slideable member and adapted to be actuated on its pivotal mounting by the sliding movement of the member and positioned over the mouth when the slideable member is at the mouth end of the bowl and juxtaposed to the side of the bowl when the slideable member is at the stem end of the bowl.

30 3. A smoking pipe as claimed in claim 2, wherein the slideable member is mounted on the side of the bowl opposite the side from which the stem extends.

35 4. A smoking pipe as claimed in claim 2, wherein the closure plate is arranged with flanged portions at the margins thereof adjacent the pivotal mounting thereof on the slideable member, said flanged portions being adapted to engage the portion of the bowl around the chamber mouth to space the plate from the mouth and prevent heating of the plate.

45 5. A smoking pipe as claimed in claim 2, wherein the closure plate is pivoted at one end to the slideable member and the opposite end is folded over to extend in spaced relation to the body of the plate and provides the plate with a cool portion.

50 6. A smoking pipe as claimed in claim 2, wherein the slideable member is arranged with a

finger grip at the end opposite to the end on which the closure plate is pivotally mounted to permit adjustment of the closure plate without injury to the user.

5 7. In a smoking pipe, a bowl of rectangular shape in cross section arranged with longitudinal recesses in the opposite side edges of a side, a chamber having a mouth at one end of the bowl and an integral stem at the opposite end extending laterally from a side of the bowl opposite the recessed side and having a bore communicating with the chamber, a member having flanged ends slidably engaging the recesses of the bowl with the member spanning the recessed side to permit adjustment of the member from one end of the bowl to the other end, and a closure plate for the chamber mouth pivotally connected to the member and adapted to be positioned over the chamber mouth when the member is adjacent the mouth end of the bowl and juxtaposed to the recessed side when the member is adjacent the stem end of the bowl.

10 8. In a smoking pipe as claimed in claim 7, a spring arranged at the pivotal connection between the member and closure plate adapted to urge the closure plate toward the chamber mouth and recessed side of the bowl.

15 9. In a smoking pipe as claimed in claim 7, abutments arranged in a recess of the bowl to limit the sliding adjustment of the member.

20 10. In a smoking pipe as claimed in claim 7, wherein one of the recesses of the bowl is of greater width than the other recess, abutments arranged at the opposite ends of the recess of greater width and out of the path of travel of the flanged ends of the member, and the flanged end engaging said recess of greater width being arranged with a projection to engage said abutments and limit the movements of the member.

25 11. In a smoking pipe, a bowl of rectangular shape in cross section arranged with an elongated circular chamber having a mouth at one end of the bowl and an integral stem at the opposite end extending laterally from a side of the bowl having a bore communicating with the chamber, and a closure plate for the mouth of the chamber of rectangular shape corresponding to the size and shape of the bowl and having a circular center portion raised from and connected to the body of the plate at spaced sections of the periphery thereof to form air passages between the circular and body portions of the plate, said closure plate being pivotally and slidably mounted to extend over the chamber mouth in one extreme position and to extend juxtaposed to another side of the bowl in the other extreme position with the mouth exposed.
